(57) **CLAIM**

The ornamental design for a foldable fire starter, as shown and described.

DESCRIPTION

FIG. 1 is first perspective view of a foldable fire starter, showing my new design;

FIG. 2 is front side view thereof;

FIG. 3 is a back side view thereof;

FIG. 4 is a right side view thereof, the left side view being a mirror image thereof;

FIG. 5 is a top side view thereof; and,

FIG. 6 is a bottom side view thereof.

The broken lines in the drawings depict portions of the foldable fire starter that form no part of the claimed design.
